UNITED STATES PATENT OFFICE.

LEROY L. TULEY, OF WOOD RIVER, ILLINOIS.

GLASS-TUBE CUTTER.

Application filed February 20, 1923. Serial No. 620,154.

To all whom it may concern:

Be it known that I, LEROY L. TULEY, a citizen of the United States of America, residing in the city of Wood River, county of Madison, State of Illinois, have invented certain new and useful Improvements in Glass-Tube Cutters, of which the following is a specification.

In the use of glass tubing in chemical laboratories and for glass gauges for steam boilers, oil stills and the like, there is a large percentage of waste due to breakage in cutting the desired lengths. The requisite length of tubing for any particular purpose is ordinarily obtained from the stock lengths by creasing with a file and breaking near the crease. This method is unsatisfactory, the crease is irregular, the edges are likewise rough and irregular and generally the portion removed is destroyed and not infrequently it is necessary to cut one or two stock lengths before a piece of tubing of the desired length is obtained.

The object of the invention is to produce a glass cutter particularly adapted to the cutting of tubes, reducing or eliminating the high percentage of loss now prevailing. The applicant's device which has proved exceedingly successful in this capacity consists of a pair of pliers having one jaw adapted to engage the outer surface of the tube and the other jaw provided with a cutter which may be of the wheel type or a diamond point.

As shown the pliers or tongs have two points of engagement on one jaw spaced apart and opposed to the cutter so that when the cutter is in operation the tube is engaged by the two abutments and the cutter at three points approximately 120° apart. This is, however, only the preferred arrangement which may be considerably varied within the scope of my invention.

The pliers are preferably adjustable after the manner of the common type of automobile pliers and the engaging points opposite the cutter may to advantage be cushioned to prevent vibration and consequent breakage.

In operation the tube is engaged by the pliers and a moderate amount of pressure applied, the pliers being rotated or oscillated about the tube until it is creased by the cutter to the desired depth when the pliers are disengaged and the tube is broken on the crease without difficulty and with a

comparatively insignificant percentage of loss.

In accompanying drawings I have illustrated a cutter embodying my invention in the preferred form, the same being shown in conjunction with a section of the tubing being operated upon. In the drawings:

Figure 1 is a side elevation of a cutter embodying my invention showing the tube engaged thereby, the tube appearing in end elevation;

Figure 2 shows the cutter and tube, being taken from the left of the cutter as seen in Figure 1;

Figure 3 is a section on the line 3—3 of Figure 1;

Figure 4 is a fragmentary view of the jaw portion of a cutter, the construction being slightly modified.

Referring to the drawings by numerals the device as shown consists of a pair of pliers or tongs which may to advantage be constructed after the manner of the ordinary type of automobile pliers now in use, the pliers being indicated by reference character 1 and being pivotally connected by a pin or bolt 2 which is fixedly secured in one jaw member 3 and passed through a slot 4 in the other jaw member 5, the slot preferably being enlarged at the ends 6—6 and reduced intermediately at 7 the pin 2 being flattened so that in a certain relative position of the jaws the pin may be passed from one to the other end of the slot to give the desired adjustment.

As shown the jaw 5 has a concave jaw surface 8 to admit and enclose the tube, the jaw surface being provided with tube engaging abutments 9—9 preferably spaced apart as shown and the other jaw member 3 is provided intermediately of its jaw surface 10 with a cutter 11 which as shown is opposite a point intermediate the abutments. These abutments 9 are preferably of comparatively soft material as leather and are intended to have a sliding engagement with the outer surface of the tube moving relatively thereto in the direction of the circumference. As shown they are of sole leather glued or wedged in slots 15.

In the operation of the tool the tubing is grasped by the cutter as illustrated in Figure 1, the plane of oscillation of the jaws being at right angles to the length of the tube, moderate pressure is applied by gripping

the handles 12 and pressing them together and the tool is at the same time oscillated about the tube whereby the tubing is scored by the cutter. Preferably it is encircled by 5 a circumferential score. When the score reaches the desired depth the cutter is disengaged and the tube is broken along the line of the score.

It will be apparent that by and in the 10 operation of the cutter the application of undue and unequal stress to the tube in cutting is avoided and the direction of the score and extent thereof are controlled and the latter is made uniform greatly decreasing 15 the tendency to shatter the tube in cutting. By the use of the soft or cushion abutments 9 instead of rigid metal ones, vibration is eliminated and the breakage still further reduced.

20 In Figure 4 I have illustrated fragmentarily a cutter in the form of plier as described, the configuration of the cutter jaw 10 being changed to the effect that it is of a concave form as at 13, the cutter 11 being 25 centrally placed of the concavely curved jaw. The lower jaw 14 is similar to the

lower jaw 8 but less sharply concave. It is obvious that the structure may be considerably varied.

I have thus described specifically and in 30 detail a glass tube cutter embodying my invention in the preferred form. This structure has been specifically described in order that the nature and operation of the same may be clearly understood, however, the 35 specific terms herein are used descriptively rather than in a limiting sense the scope of the invention being defined in the claim.

What I claim and desire to secure by 40 Letters Patent is:

A glass tube cutter consisting of a pair of jaw members, means adjustably and pivotally connecting the jaw members, a glass cutter on one said jaw member and spaced, yielding abutments on the other jaw 45 member.

Signed by me at Wood River, Illinois, this 12th day of Feb., 1923.

LEROY L. TULEY.
